(57) **CLAIM**

The ornamental design for a battery pack, as shown and described.

DESCRIPTION

FIG. 1 is a front view of a battery pack showing my new design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The broken lines showing the remainder of the battery pack are included for the purpose of illustrating environmental structure and form no part of the claimed design.
